SAFETY RAZOR

Frederick C. Rojahn, New York, N. Y.

Application November 12, 1938, Serial No. 240,188

8 Claims. (Cl. 30—60)

This invention relates to safety razors, and this application, in part, is a continuation in part of my prior application, Serial No. 24,812, filed June 4, 1935, and, in other part, represents a carrying forward of the invention disclosed in said prior application.

The invention relates more particularly to safety razors of the type embodying a blade supporting frame, a thin, flexible blade, and means for clamping the blade in an operative position against the frame, and, generally speaking, the object of the invention is to provide a safety razor of this type in which the blade clamping means is permanently assembled with the frame against the possibility of loss therefrom and is quickly and easily operable between blade clamping and blade releasing positions.

A special object of the invention is to provide a simple, practical safety razor of the type mentioned which is of low production cost and which is thoroughly reliable and efficient in use.

Another special object of the invention is to provide a safety razor of the type mentioned in which the blade clamping means is operable between blade clamping and blade releasing positions by rotation of a part of the handle of the razor, and which embodies simple, practical means whereby rotation of the handle part imparts desired blade clamping and blade releasing movements to the blade clamping means.

Another special object of the invention is to provide a safety razor of the type mentioned embodying a container to receive lather and cuttings and which is readily accessible for cleaning purposes.

With the foregoing and other objects in view, which will become more fully apparent as the nature of the invention is better understood, the same consists in the novel features of construction, combination and arrangement of parts as will be hereinafter more fully described, illustrated in the accompanying drawings and defined in the appended claims.

In the accompanying drawings, wherein like characters of reference denote corresponding parts in related views:

Figure 1 is a side elevation of a safety razor constructed in accordance with one practical embodiment of the invention.

Figure 2 is an end elevation of the razor shown in Fig. 1, the blade clamping means being shown in blade clamping position.

Figure 3 is a view similar to Fig. 2 showing the blade clamping means in blade releasing position.

Figure 4 is a top plan view of the razor shown in Fig. 1.

Figure 5 is a central, longitudinal section through the razor shown in Fig. 1.

Figure 6 is a central, transverse section 5 through the razor shown in Fig. 1.

Figure 7 is a side elevation of a safety razor constructed in accordance with another practical embodiment of the invention.

Figure 8 is an end elevation of the razor shown in Fig. 7, the blade clamping means being shown in blade clamping position.

Figure 9 is a view similar to Fig. 8 showing the blade clamping means in blade releasing position.

Figure 10 is a side elevation of a safety razor constructed in accordance with another practical embodiment of the invention.

Figure 11 is an end elevation of the razor shown in Fig. 10, the blade clamping means being shown in blade clamping position; and

Figure 12 is a view similar to Fig. 11 showing the blade clamping means in blade releasing position.

Referring to the drawings in detail, first with particular reference to the embodiment of the invention illustrated in Figs. 1 to 6, it will be observed that the present razor includes a blade supporting frame, designated generally as A, and that this frame is of generally rectangular shape as viewed in side elevation and comprises a pair of spaced apart end plates 10, 10, a bottom plate 11 joining said end plates together at their bottoms, and a transversely arched, blade supporting top plate 12 joining said end plates together at their tops.

The razor blade, designated generally as B, may be specially constructed for use in the present razor, or it may be of a known commercial type. It is rectangular in shape, thin and flexible, sharpened along its two longitudinally extending edges, and is provided with suitable openings to receive suitable projections 13 rising from the frame top plate 11 to properly position it upon said top plate.

In each of the frame end plates 10 is a central, vertical, elongated slot 14, while extending between said end plates is a cross bar 15 carrying at its ends trunnion or pivot elements 16 which extend through said slots 14. Said bar thus is guided for vertical movement within the frame A and by vertical movements thereof imparts corresponding movements to the trunnion or pivot elements 16.

Means for clamping the blade B against the

top plate 11 comprises a pair of yoke elements C, C, each of inverted U-shape as viewed in side elevation and each comprising a blade engaging top member 17 and a pair of arms 18 depending, respectively, from the opposite ends of said top member.

The yokes C extend longitudinally relative to the frame A and have their arms 18, 18 extending downwardly over the outer faces of the end plates 10, 10, respectively, the arm at one end of each yoke being pivotally engaged with one of the trunnion or pivot elements 16 and the arm at the other end of each yoke being pivotally engaged with the remaining trunnion or pivot element 16. In this connection, it will be observed that, in order to permit such pivotal mounting of the yokes, the lower end portions of the arms 18 of one of the yokes are formed to overlie the lower end portions of the arms 18 of the other yoke. Moreover, it will be observed that, in order to facilitate such pivotal mounting of the yokes, the trunnions or pivots 16 may appropriately be in the form of shouldered screws threaded into the ends of the cross bar 15 as shown.

The yokes C, C are movable between lowered, inwardly swung, blade clamping positions in which the inner edges of their top members 17, 17 abut each other, as shown in Fig. 2, and elevated, outwardly swung positions in which the frame top plate 12 is uncovered for removal of a blade thereof or for positioning of a blade thereon, as shown in Fig. 3, and simple means are provided whereby said yokes are moved positively to said positions by downward and upward movements respectively, of the cross bar 15.

The yoke arms 18 are of substantially J-shape. That is to say, at the lower end of each yoke arm is an outwardly directed tip or hook formation 19. Moreover, a pair of pins 20, 20 project outwardly from each end plate 10 in a common horizontal plane, one to either side of the slot 14, and are so spaced apart and so positioned vertically with respect to the frame A that, upon downward movement of the cross bar 15 from its uppermost position, the outer edges of the respective yoke arms engage said pins and thereby are caused to be swung inwardly to their innermost positions, either prior to or simultaneously with movement of the cross bar 15 to its lowermost position. Also, the locations of said pins is such that, upon upward movement of the cross bar 15 from its lowermost to its uppermost position, said pins are engaged by the outwardly directed tip or hook formations 19 of the arms 18 to cause the yokes C, C to be swung outwardly to their blade access affording positions shown in Fig. 3 either prior to or simultaneously with movement of the cross bar 15 to its uppermost position. Furthermore, the bottom portions of the tip or hook formations 19 of the arms 18 preferably are shaped to engage between the pins 20, 20 and thereby hold the yokes in predetermined outwardly swung positions when the cross bar 15 is in its uppermost position. Of course, the dimensions of the parts is such that when the cross bar 15 is in its lowermost position, the top members 17, 17 of the yokes exert downward pressure upon the blade B and maintain the same transversely bowed and clamped against the top of the frame top plate 12.

Any suitable means may be provided for vertically shifting the cross bar 15 to its uppermost and lowermost positions. As illustrated in the present instance the frame A is provided with

a handle 21 for manipulating the razor. This handle is suitably fixed to and depends from the frame bottom plate 11, medially thereof, and is hollow, and contains a screw element 22 which, by any suitable means, as, for example, a ring 23 disposed in mating grooves in the handle and said screw element, is held against longitudinal movement but is permitted to rotate freely relative to said handle.

Suitably fastened at its upper end to the cross bar 15 and extending downwardly therefrom into the handle 21 and into an axial bore in the screw element 22, is a rod 24 which, at or near its lower end, is provided with a cross pin 25 disposed in a spiral slot or slots 26 in said screw member. Thus, by rotation of the screw element 22 the rod 24 and, consequently, the cross bar 15, may be moved upwardly and downwardly to move the yokes C, C to their upper, outwardly swung positions and to their lower, inwardly swung positions as is apparent.

For rotating the screw element 22 the same may be provided with a finger grip portion 27 extending below the lower end of the handle 21 and forming, in effect, a part of said handle.

Any suitable guard means adjacent to the cutting edges of the blade B may be provided. As illustrated in the present instance, a pair of closure plates 28, 28 for the sides of the frame A are provided along their upper edges with guard teeth 29 disposed suitably outwardly of and below the cutting edges of the blade B for contact with the skin in advance of said cutting edges to prevent the latter from gouging the skin.

Between the guard teeth 29 and the cutting edges of the blade B and also between said guard teeth and the longitudinal edges of the frame top plate 12 are narrow slots to permit lather and cuttings to enter the container formed by the frame A and its side closure plates 28, while in order to permit ready cleaning of said container whenever desired, the closure plates 28 are suitably pivoted to the frame A for swinging movement between open and closed positions relative thereto. In this connection and as illustrated in the present instance, the closure plates 28 are pivoted at their tops, as indicated at 30, to the frame end plates 10, 10, lips 31 are provided on the ends of said closure plates for contact with the edges of said end plates to limit inward swinging movement of said closure plates, and spring tongues 32 are provided on said closure plates for frictional engagement with the inner faces of the end plates to hold said closure plates in closed positions.

In operation, the finger grip element 27 first is rotated to move the yokes C, C to their upper, outwardly swung positions illustrated in Fig. 3 to permit the positioning of a blade B upon the top plate 12 and then is rotated to move said yokes to their lower, inwardly swung, blade clamping positions. The razor then is ready for use. When in use, lather and cuttings enter the container formed by the frame A and its side closure plates 28 and, whenever desired, said closure plates may be swung open to permit cleaning of said container. After use, the finger grip element 27 again is rotated to move the yokes C, C to their upper, outwardly swung positions to permit removal of the blade, whereupon, after cleaning, the yokes may be moved to their closed positions until the razor is again to be used.

As will be apparent, the yokes C, C are positively controlled in their movements, the blade clamping means are desirably permanently as-

sembled with the razor, and the razor may be produced at low cost because it embodies few parts which are capable of economical production and assembly.

5 Referring now to the form of the invention illustrated in Figures 7 to 9, it will be observed that the same is of generally the same construction and the same mode of operation as the form of the invention illustrated in Figures 1 to 6, except that the blade clamping means comprises only a single yoke element designated as C'. Therefore, the details of construction illustrated in Figs. 1 to 6 are not repeated.

The yoke element C' comprises a top member 17' having arms 18' depending from the ends thereof over the frame end plates 10' and pivotally mounted on the screws 16'. The arms 18' are of substantially J-shape. In other words, each arm is provided at its lower end with a laterally extending tip or hook formation 19' to engage a related pin 20' projecting outwardly from the related end plate 10 to cause the yoke element to be swung to its Fig. 9 position to afford access to the top of the frame A' for blade applying or removal purposes when the cross bar (not shown) is moved to its uppermost position. The other pins 20' are located slightly above said first mentioned pins to permit said swinging movement of the yoke element and to be contacted by the edges of the arms 18' opposite the edges thereof from which the tips or hook formations 19' project, to prevent swinging movement of the yoke elements in the opposite direction. As shown, the pins 20' are located sufficiently far above the tips or hook formations 19' when the yoke element is in its lowermost position so that swinging of the yoke element occurs only when it is near its uppermost position. In other words, initial upward movement and final downward movement of the yoke element is desirably vertically straight.

Referring now to the embodiment of the invention illustrated in Figs. 10 to 12, it will be observed that the construction is, generally speaking, simply a reversal of the construction illustrated in Figs. 7 to 9. In other words, instead of having hook formations on the arms 18^a of the single yoke element C^a for cooperation with pins on the frame end plates 10^a, the slots 14^a in said end plates are provided at their upper ends with lateral extensions 14^b and each yoke arm 18^a is provided, at a suitable point above its pivotal connection 16^a with the cross bar (not shown), with a pin 20^a operating in its related slot. As is apparent, when the yoke element is moved upwardly, the pins 20^a, by riding into the lateral extensions 14^b of the slots 14^a, causes the yoke element to be swung laterally to uncover the top of the frame A^a for blade applying or removal purposes. Moreover, it is apparent that, upon downward movement of the yoke element, the pins 20^a first cooperate with lateral extensions 14^b of the slots 14^a to cause the yoke element to be swung inwardly, and then cooperate with the straight, vertical portions of said slots to guide the yoke element for straight line downward movement.

Figures 10 to 12 further illustrate that the frame closure plates 28^a may be pivoted at their bottoms to the frame A^a. As is obvious, the means for causing swinging of the yoke element, or elements, as the case may be, may, according to any of the forms of the invention, be confined to one end only of the razor. Moreover, 75 and as is further obvious, the frame closure

plates may, according to any of the forms of the invention, be eliminated and guard means for the cutting edges of the blade may be provided directly on the blade supporting frame or in any other suitable manner.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:

1. A safety razor blade holder comprising a frame having an arched blade holding head and end plates connected thereto and a base plate connecting the end plates in spaced relation to each other, a tubular handle connected to the base, the end plates having vertical slots there- 20 in, a cross rod having ends slidable in the slots, a yoke shaped blade clamping member providing side arms pivotally connected with the ends of the cross rod, a screw carried by the handle for propelling the cross rod to lift the yoke 25 shaped blade clamping member above the blade holding head, and a pin on one of the end plates engageable by one of the side arms to swing the blade clamping member laterally of the holding 30 head.

2. A safety razor blade holder, comprising a tubular handle and a blade holding frame, said frame including a base member directly fixed on the upper end of the handle and upstanding side plates and an arched blade holding member connected to said side plates, a tubular screw arranged in the handle, a cross bar slidable on the frame and having ends slidable through the side plates, and an arched blade clamping member having end arms slidable against the outer 40 faces of the side plates and pivotally connected to the ends of the cross bar, the cross bar having an operating rod working in the screw and provided with a pin engaging the thread of the screw so that upon turning of the screw the rod 45 is moved to lift and lower the arched blade clamping member.

3. A safety razor blade holder consisting of a tubular handle, a blade supporting frame mounted on the tubular handle and including end 50 plates having vertical slots, a hollow screw in the handle having swivelled connection therewith, said screw having a fast thread extending through the wall thereof, a rod extending through the screw and having a pin extending 55 through said thread, a cross bar connected to the upper end of the rod and having sliding engagement at its ends with the slots of the end plates, a U-shaped blade clamping member pivotally connected with said cross bar, and pins located 60 on said end plates to cause said U-shaped clamping member to swing laterally when elevated by the turning effect of the screw upon the pin of the vertical rod.

4. A razor comprising a blade supporting frame, a tubular handle carried by said frame, a shaft reciprocable in the tube, a cross member carried by said shaft, a clamping plate having an arm pivoted to said cross member, said arm having a J-shaped end, and means carried by the frame 70 engaging the arm near the tip of the J when the shaft is moved in one direction to throw the clamping member on its pivot to blade releasing position and when the shaft is moved in the other direction engaging the stem of the J 75

to throw the clamping member on its pivot to blade clamping position.

5. A safety razor comprising a blade supporting frame including a top wall, a bottom wall and end walls connecting said top and bottom walls, a member for clamping a blade upon said top wall, arms on said member extending downwardly over said end walls, a vertically movable cross member within the frame, means for vertically moving said cross member, pivotal connections between said cross member and the arms of said clamping member, and formations on said arms and on the end walls of said frame cooperating to cause said clamping member to be swung laterally outward to blade releasing position when said cross member is moved upwardly and to cause said clamping member to be swung inwardly to blade clamping position when said cross member is moved downwardly.

10. 6. A razor comprising a blade supporting frame, a handle for said frame, a cross bar within said frame, means guiding said cross bar for vertical movement relative to said frame, means for vertically moving said cross bar, a blade clamping plate having arms pivoted to said cross bar, at least one of said arms having a hooked end, and means on the frame cooperating with said hooked end to swing said blade clamping plate laterally with respect to the frame when the cross bar is moved upwardly.

15. 7. A razor comprising a blade supporting frame including end plates, a bottom plate and a top blade supporting plate, a handle for said frame, the end plates having vertical slots, at least one of said slots having a lateral extension at its upper end, a cross bar within said frame, trunnion elements on the ends of said cross bar extending through said slots, means for vertically moving said cross bar relative to said frame, a blade clamping member having arms pivotally mounted on said trunnion elements, and a pin on at least one of said arms disposed in the slot having the lateral extension for cooperation with said lateral extension to swing the blade clamping member laterally with respect to the frame when the cross bar is moved upwardly relative to the frame.

20. 8. A razor comprising a blade supporting frame, a handle for said frame, a cross member guided for vertical movement relative to said frame, means for vertically moving said cross member, a pair of blade clamping plates each having depending arms at its ends pivoted to said cross bar, said arms having hooked lower ends, and means on said frame cooperating with the hooked ends of said arms to swing said blade clamping plates laterally outward with respect to said frame when the cross member is moved upwardly.

FREDERICK C. ROJAHN. 30
